MASSACHUSETTS

SHOE SHANK STIFFENER

Application filed March 27, 1931. Serial No. 525,712.

This invention relates to shoe shank stiffeners particularly applicable to shoes having extremely high heels and narrow shanks. Shoes of this type commonly have little or 5 no upper materials at the central portion of the shank so that the relatively narrow sole and the shank stiffener at this portion of the shoe are called upon to resist the entire stresses of service at the shank. These stresses 10 are particularly severe due to the extreme height of the heel, the heel acting as a long lever to bend the shank of the shoe when the weight of the wearer, which tends to spread the top lift of the heel backwardly is imposed thereon. These stresses are most severe 15 at about the breast line of the heel.

The stiffener of the present invention therefore is preferably constructed continuously tapering forwardly from a point a little forwardly of the breast line to come within the 20 stitch line of a McKay shoe, which is a type of shoe often made in this extreme style, and yet be of maximum width throughout substantially the length of the shank, the portion 25 forwardly of the heel seat comprising a rib or corrugation to add to its strength. The laterally convex side of the rib is downwardly faced to give the desired rounded contour to the outersole but at the breast line of the 30 shoe the stiffener is provided with marginal flat flanges. These prevent the edges of the corrugation or rib from cutting into the innersole under the pressure of the heeling operation and the weight of the wearer. 35 These marginal flat flanges also act as fillers on either side of the rib just forwardly of the heel breast where the shoe widens sharply. The flanges are cut off sharply to insure 40 against riding up on the inturned portions of the upper where these are lasted over. Shoes of this type are often made on wood lasts which afford no means of clinching a 45 fastening element at the forward end of the shank stiffener. Means by which the fastening may be done entirely at the heel end and yet cause the forward end of the stiffener to press firmly against the innersole is therefore provided, but in order that advantage may be taken where the last has a metal 50 clinching insert adjacent to the break line of

the sole the stiffener may be formed to receive a fastener at its forward end also.

For a more complete understanding of this invention, reference may be had to the accompanying drawing in which

55

Figures 1 and 2 are plan and side elevations, respectively, of the stiffener.

Figures 3 and 4 are sections on lines 3—3 and 4—4, respectively, of Figure 2.

Figure 5 is a fragmentary bottom plan 60 of a lasted shoe before the application of the outersole and showing the stiffener in position.

Figure 6 is a fragmentary section through a completed McKay shoe substantially on the 65 line 6—6 of Figure 5.

Figures 7 and 8 are side elevations partly broken away and in section of a shoe showing different methods of securing the shank 70 stiffener in position.

Figure 9 is a detail section on line 9—9 of Figure 5.

75

As shown in the drawing the stiffener comprises a strip having a central laterally curved rib or corrugation 1 extending for the 75 major portion of its length. At its forward end it is substantially flat laterally and is turned upward slightly as at 2 and as shown in Figures 1 and 2 it is preferably provided with an opening 3 to receive a fastening element such as a tack, which, however, as will later appear is not always used. At each side of the rib 1 at its rear end is positioned a substantially flat flange portion 4 which merges with a substantially flat or preferably 80 slightly upwardly concaved rear portion 5 extending rearwardly of the rib. As shown the end of this portion 5 is provided with a slight concavity as at 6 which mates the convexity 7 of the forward end, the stiffener being cut from a single strip of material in 85 end to end relationship. The forward end of the stiffener is cut convex in order that it may present no sharp angles which might tend to cut into the adjacent portion of the shoe. At the rear end the end configuration is of no particular consequence so that it may be left concave as results from the cutting off of the strip for successive stiffeners with the 90 convex formation for the forward end. The 95

100

lengthwise portion of the stiffener provided with the flanges 4, which is within the rear half of its length, is substantially wider than the portion forwardly of the flanges, the flanges terminating at their forward ends quite abruptly. Forwardly thereof the full width of the stiffener is formed by the rib or corrugation 1. This stiffener is shown as symmetrical about a longitudinal axis so that the same stiffener is applicable to either a left or a right shoe and both its wider and narrower portions forwardly of the rear end of the stiffening rib taper forwardly.

The flange portions 4 terminate somewhat forwardly of the breast line of the heel of the shoe to which the stiffener is designed to be applied, this being substantially on the section line 6—6 of Figure 5. These flat flanges portions take the pressure from the heel nail-
ing mechanism and also from the weight of the wearer during service, distributing it over a substantial area of the sole so as not to cut into the sole as might be the case were the edges of the rib portion brought directly into contact with the sole at this portion of the shoe. The forward ends of these flanges which project forwardly of the breast line act as fillers on opposite sides of the rib where the shoe widens substantially from its narrow portion. At the narrowest portion the rib of the stiffener may project over the lasted-in upper materials but it must be narrow, particularly where the shoe is of the McKay type in order to provide room for the McKay stitching, the position of which is substantially as shown by the dotted lines *a* in Figure 5 and in full lines in Figure 9. As shown in Figure 9 the edges of the rib approach closely to the McKay stitches and the rib being downwardly convexed it forms the outersole 10 of the shoe to the desired downwardly convexed curvature at the shoe shank. Figure 6 shows also the manner in which the flange portions 4 extend out beneath the lasted-in portions of the upper at the heel seat, serving as a filler.

Where the shoes are made on lasts which have a metal insert forwardly of the break line, the stiffener may be fixed at its forward end by driving a tack 15 at its forward end and at its rear end by driving a tack 16 through one of a pair of holes 17 and 18 at the rear portion of the stiffener. In many cases, however, shoes of this extreme type are made on lasts unprovided with metal inserts adjacent to the break line of the sole against which fasteners may be clinched, and in such cases some other means of securing the stiffener must be provided. The rear end portion of the stiffener 5 is shown as slightly upwardly concave and with such construction, when fastening tacks are driven through both the holes 17 and 18, the stiffener is flattened somewhat at its concaved portion and the forward end of the stiffener is sprung

up firmly against the innersole so that it is securely held in position without the necessity of passing a tack through the hole 3. This is illustrated in Figure 8 wherein the two tacks 20 and 21 are shown as driven through the holes 17 and 18 of the stiffener and into the innersole.

In Figure 5 the shoe is shown as lasted and this lasting may be done by such well known processes as the McKay or cement processes. When done according to the McKay process there would of course be lasting tacks positioned to hold the upper materials in lasted condition before the outer sole is applied. With the cement process no such lasting tacks would be used.

In the construction illustrated the stiffener is of maximum strength at about the heel breast line of the shoe where the maximum stresses are exerted thereon, the stiffener at this point being provided with the central stiffening rib portion of the greatest width and having the lateral flanges which prevent the stiffener from cutting into the sole material. Hence the maximum amount of strength and stiffness for a given weight of material is found at this point. Forwardly of the heel breast line and throughout the narrower portion of the shank the stiffener is of sufficiently narrow dimensions to pass between the lines of McKay stitching and yet is reinforced by its rib construction for maximum strength consistent with the narrow construction.

From the foregoing description of an embodiment of this invention, it should be evident to those skilled in the art that various changes and modifications might be made without departing from the spirit or scope of this invention as defined by the appended claims.

We claim:

1. A shoe shank stiffener having a portion within its rear half substantially wider than its forward portion and provided throughout the major portion of its length with a stiffening rib, said wider portion only having flat marginal flanges on either side of said rib.

2. A shoe shank stiffener having a portion within its rear half substantially wider than its forward portion and provided throughout the major portion of its length with a stiffening rib, said wider portion only having flat marginal flanges on either side of said rib, the portion forwardly of said wider portion tapering in width forwardly.

3. A shoe shank stiffener symmetrical with respect to a longitudinal axis and having a portion within its rear half substantially wider than its forward portion, and provided throughout the major portion of its length with a stiffening rib, said wider portion only having flat marginal flanges on either side of said rib.

4. A shoe shank stiffener symmetrical with

- respect to a longitudinal axis and having a portion within its rear half substantially wider than its forward portion, and provided throughout the major portion of its length with a stiffening rib, said wider portion only having flat marginal flanges on either side of said rib, the portion forwardly of said wider portion tapering in width forwardly.
5. In a shoe, a shank stiffener having a substantially widened portion terminating at points slightly in advance of the heel breast line, said portion including a central rib and side flanges extending laterally from said rib, said rib only extending forwardly from said widened portion and constituting the forward portion of said stiffener.
6. In a shoe, a shank stiffener having a substantially widened portion terminating at points slightly in advance of the heel breast line, said portion including a central rib and side flanges extending laterally from said rib, said rib only extending forwardly from said widened portion and constituting the forward portion of said stiffener and tapering in width forwardly.
7. In a shoe, a shank stiffener symmetrical about a longitudinal axis and having a substantially widened portion terminating at points slightly in advance of the heel breast line, said portion including a central rib and side flanges extending laterally from said rib, said rib only extending forwardly from said widened portion and constituting the forward portion of said stiffener.
8. In a shoe, a shank stiffener symmetrical about a longitudinal axis and having a substantially widened portion terminating at points slightly in advance of the heel breast, said portion including a central rib and side flanges extending laterally from said rib, said rib only extending forwardly from said widened portion and constituting the forward portion of said stiffener and tapering in width forwardly.
- In testimony whereof we have affixed our signatures.
